BUBBLE CAP AND DOWN-PIPE UNIT

John A. Gibb, Northport, N. Y., and James F. Thornton, Los Angeles, Calif., assignors to The Lummus Company, New York, N. Y., a corporation of Delaware

Application August 31, 1942, Serial No. 456,738

6 Claims. (Cl. 261—114)

This invention relates to liquid-vapor contact devices and particularly to an improved form of a combined bubble cap and downpipe unit.

In distillation and like operations involving the repeated contact of streams of liquid and of vapor with each other, it is essential for most efficient performance to obtain the maximum possible contact of these two streams. In order to achieve this purpose, it has heretofore been suggested to utilize a combined bubble cap and downpipe construction in lieu of the customary bubble cap deck construction. Many such suggestions have been made; but the proposed constructions, particularly when employed in small diameter fractionation columns, for example, are generally open to the objections that the downpipe area, the liquid-vapor contact area, and/or the riser area are limited or restricted in some undesirable manner.

It is the principal object of our invention to provide an improved bubble cap and downpipe construction.

It is a further object of our invention to provide a combined bubble cap and downpipe unit particularly for use in a small diameter column whereby the maximum provision for the downflow of liquid, for the contact of liquid and vapors, and for the upward flow of vapors is provided.

Still further objects and advantages of our invention will be apparent from the following description of a preferred form of embodiment thereof taken in connection with the accompanying drawing, of which:

Fig. 1 is an elevation view, partly in section, of a fractionating column provided with our improved bubble cap and down-pipe unit;

Fig. 2 is a view taken substantially along the line 2—2 of Fig. 1;

Fig. 3 is a view taken substantially along the line 3—3 of Fig. 1;

Fig. 4 is a view taken substantially along the line 4—4 of Fig. 1;

Fig. 5 is a detailed view of the bubble cap portion of our combined unit.

In Fig. 1, we have shown a fractionating column 10 of small diameter provided with a plurality of our improved bubble cap and downpipe units 12 superimposed one upon the other. Each of these units includes a downpipe 14, preferably concentrically positioned within column 10, for the downward flow of liquid through this column. This downpipe is provided near its upper end with an annular trough or gutter 16 for the collection of the down-flowing liquid from the next

upper bubble cap and downpipe unit. This trough comprises the annular ring or plate 16 and the upwardly extending flange 18 at the outer periphery or perimeter of the plate, which may be made integral with such flange as shown if desired. The upper edge of this flange desirably extends above the upper edge of downpipe 14 to insure that the downflowing liquid passes into the downpipe. Plate 16 may be attached to downpipe 14 in any suitable fashion; for example, it may be bolted thereto as by means of stud bolts 20 and nuts 21 to flange 22 on downpipe 14. A gasket 22a may be provided to effect a liquid-tight seal. The upper edge of downpipe 14 may be desirably serrated as shown at 23 for more even distribution of the downflowing liquid thereinto; and, in such case, the upper edges of downpipe 14 and of flange 18 may be at substantially the same level if so desired. It will be noted that trough 16 also serves as the vapor riser portion of our combined unit.

According to our invention, column 10 is provided with an inwardly extending annular ring or plate 25 positioned above the upper edges of the downpipe and the flange 18. At its inner periphery, this plate has a downwardly extending flange 26, the lower edge of which extends between downpipe 14 and flange 18 below the upper edges thereof and below the level of liquid maintained on trough 16. Annular plate 25 and flange 26 may be made integral with each other as shown if desired. Thus, the rising vapors flow from annular space 27 into the annular vapor riser space 28 between flange 18 and the wall of column 10, thence through the annular space 29 between flange 18 and flange 26, and finally through the annular space 30 between flange 26 and downpipe 14. During such flow these vapors are, of course, forced to pass through the liquid on trough 16. Plate 25 and flange 26 thus comprise the bubble cap portion of our improved combined unit. To provide a better contact of these vapors with this liquid, the lower edge of flange 26 is desirably serrated as at 26a. The serrations in the downpipe 14 and in the flange 26 are so arranged that the level of liquid on trough 16 is always maintained above the serrations 26a so that the maximum contact of the vapors with the liquid is assured.

Plate 25 may be attached to the wall of column 10 by any suitable means. Alternately, however, it may be supported on and by trough 16 as shown. For this purpose, plate 25 is provided with a plurality of supporting members 31, which rest on the upper edge of flange 18. For this

reason, the upper edge of flange 18 is desirably not serrated. These supporting members may be made integrally with plate 25 and flange 26 if desired. Flange 26 is also provided with a plurality of lugs 32, whereby plate 25 is securely fastened to plate 18 as by means of the stud bolts 33 and the nuts 34.

Downpipe 14 is provided at its lower end with a tray 35 for the collection of the liquid flowing downwardly therethrough. This tray constitutes the downpipe seal pan of our combined unit. For the proper distribution of the downflowing liquid onto the next lower bubble cap and downpipe unit, tray 35 is provided at its outer periphery with an upwardly extending flange 36, which is desirably serrated as at 37 so that the liquid can be more evenly distributed in a plurality of small streams. This tray may be attached to the lower edge of downpipe 14 in any suitable manner as by welding, for example. Accordingly, downpipe 14 is provided with a plurality of openings 38 in the lower portion thereof for the passage of the downflowing liquid onto tray 35. The upper edge of flange 36 desirably extends above these several openings to provide the necessary vapor seal. In the preferred form of embodiment of our invention, suitable provision is made so that each bubble cap and downpipe unit rests on and is separated by the next lower unit. For this purpose, flange 36 is desirably provided with a plurality of outwardly extending lugs 40, which may be made integral therewith. Each of these lugs is suitably slotted as at 41 for the insertion of a ring-supporting member 42, which is suitably fastened to the respective lug after insertion therein as by means of rivets 43. If desired, members 42 may be slidably attached to the respective lugs 40 so that some degree of flexibility results. These members 42 support a ring 46, which is likewise attached thereto as by rivets 47. The lower edge of this ring is encased in a suitable gasket material 48, which is held in place with respect to ring 46 by means of the plurality of rivets 49. If desired, this gasket 48 may comprise a suitable gasket material provided with a flexible metallic cover. When the several bubble cap and downpipe units are inserted in column 10 one above the other, the effect of the weight of such units is to compress the gasket 48 downwardly against flange 25 and outwardly against the wall of column 10. In this way, a substantially tight seal is made with the column wall, and vapor leakage around each unit is substantially prevented.

Our improved bubble cap and downpipe construction has several features which particularly characterize it. The primary features are the provision of an exceptionally large downpipe 14 or downflow area in the center of the column and the provision at the same time of an exceptionally large vapor riser area 28 around the downpipe. This riser area may be as much as 30% or more of the superficial tower area instead of the customary 15% or less. It will thus be seen that a column provided with our improved units has a very much greater vapor-handling capacity than the ordinary bubble deck column. For example, in a column having a diameter of 24 inches, the following dimensions are suitable. The diameter of downpipe 14 is 10 inches; the outer diameter of annular plate 16 is 20 inches; and the inner diameter of annular plate 25 is 15 inches. In this case, the downpipe area is approximately 78.5 square inches, and the riser area (annular space 28) is approximately 138

square inches (cross-sectional area of column (452 square inches) less area of plate 16 and downpipe 14 (314 square inches)). Since the superficial area of the column (total cross-sectional area of the column (452 square inches) less the cross-sectional area of the downpipe (78.5 square inches)) is approximately 373.5 square inches, the riser area is about 30.5% of the superficial area of the column. This percentage compares favorably with the customary 15% or less.

Furthermore, this improved construction provides a relatively large slot area for the contact of the rising vapors with the liquid maintained on trough 15. In the above example, the slotted circumference of the bubble cap portion is approximately 47.1 inches, and a very effective turbulence around the slots on this cap portion is provided. In addition, a prolonged contact of the vapors with the liquid is provided by the passage of the rising vapors through the liquid spray which is caused by the overflow of liquid from tray 35. The diameter of this tray 35 is desirably substantially the same as the inner diameter of plate 25 but may also be somewhat greater where such construction improves the vapor-liquid contact. Preferably, the respective annular areas 28, 29, and 30 are made as nearly equal as possible so as to reduce the pressure drop therethrough to as low a degree as possible although annular area 30 may be somewhat less than either of the other two. In the above example, the annular area 28 is 138 square inches as already noted; the annular area 29 is 137.5 square inches (cross-sectional area of plate 16 (314 square inches) less cross-sectional area of plate 25 (176.5 square inches)); and the annular area 30 is 98 square inches (cross-sectional area of plate 25 (176.5 square inches) less cross-sectional area of downpipe 14 (78.5 square inches)).

The spacing between respective units in a column may be any distance that is found desirable or necessary. In addition, provision (not shown) may be made for separating entrained liquid between each pair of units.

Our improved bubble cap and downpipe construction is particularly applicable for use in small diameter columns ranging from 6 to 24 inches in diameter. In such case, each column is desirably provided with a plurality of such units superimposed one upon the other. Our invention is also applicable, however, for use in columns of larger diameter. In such case, multiple superimposed bubble cap and downpipe units are used in any suitable fashion. Although we have described our invention in connection with a circular column, it is equally applicable to a column having any other type of cross-sectional area. In all cases, however, downpipe 14 is preferably positioned substantially centrally within the column.

Furthermore, our improved device is useful in the deaeration of water such as boiler feed water. In such case the water descends through the column in countercurrent contact with steam. Because of the large contact area between the downflowing liquid and the rising vapors which our construction provides, deaeration of the water is readily accomplished without any appreciable loss of steam.

Although we have described a preferred form of embodiment of our invention, we are aware that modifications may be made; therefore, only

such limitations as appear in the claims appended hereinafter should be applied.

We claim:

1. A plurality of combined bubble cap and downpipe units for a fractionating column, said units being in superimposed relation and each unit comprising a downpipe for liquid, a liquid-collecting trough attached to said downpipe near the upper end thereof, said trough having at its outer periphery a flange, the upper edge of which extends above the upper edge of the downpipe, a bubble cap comprising an annular baffle provided at its inner periphery with a downwardly extending flange, the lower edge of which extends below the upper edges of the downpipe and the first flange, said annular baffle being adapted to fit the wall of the column and being positioned above the downpipe, a plurality of spaced supporting members attached to the under and outer sides of the bubble cap forming baffle and flange, said supporting members resting on the upper edge of the trough flange, means to fasten the bubble cap to the trough, a tray attached to the lower end of the downpipe to collect the liquid flowing downwardly therethrough and to distribute such liquid onto the next lower unit, a plurality of spaced outwardly extending lugs attached to said tray, a ring-supporting member carried by each lug, and a ring supported by and attached to said latter members, said ring resting on the bubble cap of the next lower unit.

2. A combined bubble cap and downpipe unit for a fractionating column formed independently of said column and comprising a relatively large diameter vertical downpipe centrally located within the cross section of the column and free from internal obstruction throughout its length, means borne by said downpipe in a fixed relation thereto forming an annular liquid-accumulating trough surrounding the upper end portion of said downpipe and with its outer side spaced materially inward from the inner wall of the column to define therebetween an annular vapor flow space, the outer side of said trough extending above the level of the upper end of the downpipe, and an annular baffle supported in the unit in a fixed position spaced above the upper edge of the outer side of the trough and including at its inner periphery an annular flange depending into the trough to a level below that of the upper edge of the downpipe, said flange being located intermediate the opposite side walls of the trough and the baffle with its flange forming, in effect, a bubble cap, and the trough, the baffle and the column together defining a single annular vapor upflow passage to constrain all the vapor ascending within the column around the exterior of the downpipe to pass through liquid accumulated in the trough.

3. A combined bubble cap and downpipe unit for a fractionating column formed independently of said column and comprising a relatively large diameter vertical downpipe centrally located within the cross section of the column and free from internal obstruction throughout its length, means borne by said downpipe in a fixed relation thereto and forming an annular liquid-accumulating trough surrounding the upper end portion of said downpipe and with its outer side spaced materially inward from the inner wall of the column to define therebetween an annular vapor flow space, the outer side of said trough extending above the level of the upper end of the downpipe, an annular baffle supported in the unit in a fixed position spaced above the upper

edge of the outer side of the trough and including at its inner periphery an annular flange depending into the trough to a level below that of the upper edge of the downpipe, said flange being located intermediate the opposite side walls of the trough and the baffle with its flange forming, in effect, a bubble cap, and the trough, the baffle and the column together defining a single annular vapor upflow passage to constrain all the vapor ascending within the column around the exterior of the downpipe to pass through liquid accumulated in the trough, and liquid collecting and distributing means attached to the lower end of the downpipe to collect the liquid flowing downwardly therethrough, form of the collected liquid a seal to close the lower end of the downpipe and also cause a distributed overflow of the liquid downward from the unit.

4. A plurality of superimposed bubble cap and downpipe units for a fractionation column and including an upper unit and a lower unit each according to claim 2, and wherein the upper unit includes liquid collecting and distributing means to collect the liquid delivered by its downpipe, form of the collected liquid a seal to close the lower end of the downpipe and also distribute the overflow of said liquid into the trough of the lower unit, said liquid collecting and distributing means being supported in the upper unit in a fixed relation to the lower end of the downpipe.

5. A plurality of superimposed bubble cap and downpipe units for a fractionation column and including an upper unit and a lower unit, each of said units comprising a vertical downpipe of relatively large diameter centrally located within the cross-section of the column and free from internal obstruction throughout its length, means forming an annular liquid-accumulating trough surrounding the upper end portion of the downpipe and with its outer side spaced materially inward from the inner wall of the column to define therebetween an annular vapor flow space, the outer side of the trough extending above the level of the upper end of the downpipe, and an annular baffle spaced above the upper edge of the outer side of the trough and including at its inner periphery an annular flange depending into the trough to a level below that of the upper edge of the downpipe, said flange being located intermediate the opposite side walls of the trough, said baffle with its flange forming in effect a bubble cap, and the trough, the baffle and the column together defining a single annular vapor upflow passage to constrain all the vapor ascending within the column around the exterior of the downpipe to pass through liquid accumulated within the trough, the upper unit including a liquid-collecting and distributing means to collect the liquid delivered by its downpipe, form of the collected liquid a seal to close the lower end of the downpipe and also distribute the overflow of said liquid into the trough of the lower unit, and the upper unit also including means to support it upon the annular baffle of the lower unit, said supporting means including annular compressible sealing means to form a seal between the outer edge of the baffle of the lower unit and the inner wall of the column, the upper unit being vertically shiftable within the column for insertion and removal.

6. In combination with the vertical shell of a fractionation column, a combined bubble cap and downpipe unit within said shell and formed independently thereof and comprising a vertical downpipe of relatively large diameter centrally

located within the cross section of said shell and of relatively large diameter for large flow capacity, an annular member borne by said downpipe in a fixed relation thereto and forming an annular liquid-collecting trough surrounding the upper end portion of the downpipe and with its outer side spaced materially inward from the inner wall of the shell to define therebetween an annular vapor flow space, the outer side of said trough extending above the level of the upper end of the downpipe, an annular baffle supported in the unit in a fixed position spaced above the upper edge of the outer side of the trough and having at its inner periphery an annular flange depending into the trough to a level below that of the upper edge of the downpipe, said flange being located intermediate the opposite side walls

of the trough, the baffle and its flange forming, in effect, a bubble cap, and the trough, the baffle, and said shell together defining a single annular vapor upflow passage to constrain all of the vapors ascending within the shell around the exterior of the downpipe to pass through liquid accumulated within the trough, and a liquid-collecting and distributing pan secured within the unit and disposed at the lower end of the downpipe to collect the liquid delivered by the latter and form of the collected liquid a seal and also cause a distributed overflow of the liquid, said shell and said unit being formed to render the unit vertically shiftable bodily within the shell for insertion or removal.
